UNITED STATES PATENT OFFICE.

WILLIAM R. HOWARD, OF WASHINGTON, DISTRICT OF COLUMBIA, ASSIGNOR TO
UNIVERSAL OIL PRODUCTS COMPANY, OF CHICAGO, ILLINOIS, A CORPORATION OF
SOUTH DAKOTA.

APPARATUS FOR TREATING OILS.

Original application filed September 13, 1922, Serial No. 587,919. Divided and this application filed March 31, 1924. Serial No. 703,013. Renewed June 2, 1927.

This application is a divisional of an application filed by me September 13th, 1922, as Serial No. 587,919.

This invention relates to improvements in an apparatus for treating oils, and refers more particularly to an apparatus adapted for the conversion of heavy hydrocarbon liquids into lighter and more volatile oils, suitable for the production of gasoline and 10 the like.

In carrying out this invention, the oil may be passed first through a heating zone and then introduced into a compartment or receptacle in an expansion chamber, where vaporization takes place and in which receptacle, the residue is collected. The vapors may be then subjected to a dephlegmating action and the reflux condensate returned to the expansion chamber for further treatment, 20 but out of contact with the residue. In carrying out the invention, pressure may be maintained on the entire system, or on such parts as desired. Also, if desired, the residue may be withdrawn from the receptacle in 25 the expansion chamber, and distilled at a lower or atmospheric pressure.

It is well known to those skilled in the treatment of hydrocarbon oils, that mixing the reflux condensate with the residuum, and 30 treating it, produces a residuum which is unfit for the production therefrom of asphalt or lubricating stock, due to the loss of viscosity. By withdrawing the residue continuously from the expansion chamber, as shown, 35 and subjecting it to distillation either under its latent heat or under a higher heat, I can produce lubricating oils or asphalts which are properly viscous and in great demand.

The single figure in the drawing is a view, 40 partly in side elevation, and partly in vertical section, of an apparatus for carrying out my process.

Referring more in detail to the drawing, 1 designates the raw oil inlet line, provided 45 with valve 2, and pump 3 for forcing the raw oil into the system. The raw oil is pumped to the inlet end of the heating coil 4, which heating coil may consist of a continuous coil of say 3" pipe, seated in furnace 5. The furnace 5 may be heated by means of the burner 6 in the usual manner and is provided with the stack 7. The oil, after being heated in the heating coil to a conversion tem-

perature, is passed through the transfer line 8, regulated by the valve 9, to a pan or open 55 topped container 10 suspended in an enlarged expansion chamber 11. This pan is preferably of such size proportionate to the size of the expansion chamber that it will have a capacity to hold the heated oil introduced 60 from the heating coils for a period of time sufficient to allow maximum vaporization. Vaporization takes place in this pan, the vapors being drawn off through the line 12, provided with the valve 13, to a dephlegmator 65 14, where part of the vapors will condense and fall back through the line 12. The uncondensed vapors and incondensable gas, after passing through the dephlegmator are forced to a condenser 15, where they are condensed 70 and passed to receiver 16. The receiver 16 is equipped with pressure gauge 17, liquid level gauge 18, gas outlet pipe 19, controlled by valve 20, and distillate drawoff pipe 21, controlled by valve 22. 75

The condensate formed in the dephlegmator, as above set forth, returns through the line 12 to a point in the expansion chamber proper and falls to the bottom thereof. The expansion chamber is provided with the 80 manhole plates 23 and 24, which may be removed for cleaning or for other purposes. The expansion chamber is also provided with residue drawoff pipe 25, controlled by valve 26, which residue, it may be noted, is of the 85 reflux condensate returned from the dephlegmator. In the preferred operation of the process, it is desirable that this be drawn off and kept separate, and not mixed with the raw oil for further treatment in the same 90 apparatus.

As a feature of the invention, I provide a residue drawoff pipe 27, controlled by the valve 28, direct-connected to the pan 10 in the expansion chamber. This residue drawoff 95 pipe connects to a still 29, of the usual type, seated in the furnace 30, and heated by means of the burner 31. If it is desired to use steam, it may be introduced under pressure from any extraneous source through the pipe 32, 100 controlled by the valve 33, to a perforated pipe 34, mounted in the still. The still is provided with vapor pipe 35 leading to any suitable condenser and receiver and also with residue drawoff pipe 36, provided with the 105 valve 37, leading either to a point of storage

outside of the system or back to the heating coils for further treatment, as desired.

One method of operating my process may be as follows: I pump raw oil into the heating coil 4 and heat it to a cracking or conversion temperature, of say, 750° F. The oil, after being raised to this cracking temperature, passes to the pan 10, in the expansion chamber, where upon being released from the small pipe, will vaporize, the vapors passing up through the pipe 12, where they will be subjected to dephlegmation and condensation and finally collected as described. The condensate collecting in the dephlegmator will be returned to the expansion chamber for further treatment. The expansion chamber may be maintained at the same heat as the heating coil or raised to a higher temperature by means of additional burners 40. The sides and bottom or either may be enclosed by the combustion chamber so that the flue gases from the heating coils or those generated by the additional burners will pass around the expansion chamber on their way to the stack. This higher temperature will serve to vaporize more or less of the reflux condensate returned to the expansion chamber, thus increasing the final yield of light products. It will be understood that the entire system, from the pump 3 to the receiver 16, may be maintained under a uniform pressure of the generated vapors, controlled by the valve 20 on the outlet side of the receiver. The residue, remaining in the pan 10 is drawn off through the pipe 27, to the still 29, the pressure being reduced to atmospheric by means of the pressure reducing valve 28. This reduction in pressure will cause an immediate vaporization of a large part of this residue, the vapors being drawn off through the pipe 35 and condensed and collected in a well known manner. The portion which does not vaporize by the latent heat therein contained, aided by the reduction in pressure, thus reducing its boiling point, may be subjected to further heat in the still 29 and in addition, subjected to the agitating action of steam and distilled, if desirable, to coke, the vapors being continuously drawn off. Or it may be drawn off and returned to the heating coils for further treatment.

By drawing off my residue and keeping it separate from the reflux condensate by means of the pan 10, I avoid making the oil unfit for producing lubricating stock or asphalt, and in addition, I distill it all as part of a continuous operation. It will be seen that there will be little or no waste of heat units by radiation in the residuum, being continuously drawn off from the pan 10, through the pipe 27. It will also be noted that I have a complete cycle of the residuum oil without admixture of reflux. The reflux is returned to the bottom of the expansion chamber where it may be heated to a higher temperature as described. An-

other advantage of the positioning of the pan in the expansion chamber is the fact that the preheated oil does not come in direct contact with the heated surface of the expansion chamber.

The process may be operated under a uniform pressure of from fifty to several hundred pounds, the pressure being reduced to atmospheric, subsequent to cracking, by means of the reducing valve 28, or differential pressures may be used in the cracking process, for example, a pressure of 500 pounds on the heating coil, 300 pounds on the expansion chamber, 200 pounds on the dephlegmator and 100 pounds on the condenser and receiver. The same temperature may be used throughout the cracking process or a higher temperature maintained on the expansion chamber than on the heating coil.

By operating the process as first described, under a uniform pressure of say, 125 pounds in the cracking process, and distilling at atmospheric pressure, without additional heat, other than the latent heat in the residuum, and using a gas oil from the Mid-Continent field of say, 30° Baumé, a yield of from 30% to 65% of commercial Navy specification gasoline can be obtained. The residuum is continuously drawn off and distilled in the still 29 at atmospheric pressure.

I claim as my invention:

1. An apparatus for treating hydrocarbon oil, comprising means for heating an advancing stream of oil to a cracking temperature, an enlarged reaction zone, means for passing heated oil from said stream to a compartment within said enlarged reaction zone, dephlegmating means, means connecting said enlarged reaction zone with said dephlegmating means, means for collecting a body of reflux condensate in a second compartment in said enlarged reaction zone, means for applying heat only to that compartment of the reaction zone containing the reflux condensate, and means for maintaining a superatmospheric pressure on the oil undergoing treatment in the apparatus.

2. An apparatus for treating hydrocarbon oil, comprising a heating coil and a reaction zone serially connected, dephlegmating means, means connecting said dephlegmating means with said reaction zone, means for collecting reflux condensate in a compartment in said reaction zone out of contact with the oil introduced thereto from the heating coil, means for applying heat only to said compartment of the reaction zone containing the reflux condensate, means for withdrawing unvaporized residual oil from said reaction zone, and means for maintaining a superatmospheric vapor pressure on the oil undergoing treatment in the apparatus.

3. An apparatus for treating hydrocarbon oil comprising a heating coil disposed within a furnace, a reaction chamber and dephleg-

mator serially connected, a partition member within said reaction chamber dividing the same into two compartments, means for admitting reflux condensate from said dephlegmator to one of said compartments, means for admitting the oil from the heating coil to the other of said compartments, and means for externally applying heat from the furnace to the compartment to which the reflux condensate is admitted.

4. An apparatus for treating hydrocarbon oil comprising a heating coil disposed within a furnace, a reaction chamber and dephleg-

mator serially connected, a partition member within said reaction chamber dividing the same into two compartments, means for admitting reflux condensate from said dephlegmator to one of said compartments, means for admitting the oil from the heating coil to the other of said compartments, means for moving unvaporized oil constituents from each of said compartments, and means for externally applying heat from the furnace to the compartment to which the reflux condensate is admitted.

WILLIAM R. HOWARD.
